UNITED STATES PATENT OFFICE.

EMIL H. DIEBOLD, OF NEWARK, NEW JERSEY.

SIGN.

Application filed August 5, 1927. Serial No. 210,948.

The present invention relates to signs, particularly to signs used in the outdoors in a setting of rural scenery.

Objects of the invention are to produce a neat and attractive sign which will not offend the artistic sense of a tourist and which will not obstruct the view of the landscape setting in which the sign is placed.

In the drawings:

10 Figure 1 is an elevation showing by way of illustration a sign embodying the principles of my invention.

15 Figure 2 is a cross section on the line 2—2 of Figure 1, showing the parts on an enlarged scale.

Figure 3 is a view on a different scale showing a modified form of the invention.

Figure 4 is a section on the line 4—4 of Figure 3.

20 Figure 5 is a fragmentary detail on an enlarged scale, showing the connection of the letters of the sign to the frame.

Referring to the drawings in detail, 10 designates struts or posts which may be of metal or any other suitable material, which may be sunk into the ground. In the rear of the sign I provide braces 11 connected with the struts 10 at an angle and also sunk into the ground. These braces 25 may be connected with the struts intermediate of their ends by cross members 12. Mounted upon these posts 10 are upper and lower angle members 13 and 14 upon which may be placed the letters of the sign. Each 30 letter is preferably outlined by a marginal strip or frame 15, the space within the frame being filled in with foraminous material such as used in fly screens. The foraminous material is held within the frame in any suitable manner, preferably the edges 35 of the frame, which may be of bendable metal, are bent over to form a groove 16 and to grasp between the walls thereof the edges of the screen material.

40 The letters are connected to the angle members 13 and 14 in any suitable manner as by bolts 17. By the use of the bolts the letters are made removable and interchange-

able. It will be readily understood that the sign may be varied from time to time. 50

In the device as shown in Figures 3, 4 and 5, the angle members 13 and 14 are connected at their ends by angle members 18 and the entire frame formed by the members 13, 14 and the members 18 is filled with wire screen 55 19. The letters in this form of the invention are set in the frame against the wire netting and are secured to the frame members 13 and 14 through the medium of ears 20 which are formed with the upper and lower ends of 60 the letters and are clamped between the vertical portions of the angle members and bars arranged in parallelism therewith by bolts 21, as clearly shown in Figures 4 and 5.

A sign of the character of either of the 65 modifications herein shown, it will readily be seen, will attractively display the legend desired and at the same time will not cut off the view of the landscape in the rear thereof. Such a sign may be set in the bend of a road 70 and a person driving a car will be able to see the contour of the land and may approach without danger.

Having described the invention what I claim is:

1. A sign of the character described comprising a frame, strips forming the marginal outline of letters and being secured to the frame at their lower and upper ends, and foraminous material arranged across the 75 space between the margins of said letters whereby the scenery in the rear of the sign can be seen through the margins of said letters.

2. A sign of the character described comprising a frame, upper and lower angle members included in said frame, strips forming letters, ears extending from the upper and lower ends of said letters, bars arranged in parallelism with vertical portions of said 80 angle members and means for securing the bars to the vertical portions and clamping the ears between the bars and vertical portions.

In testimony whereof I affix my signature.

EMIL H. DIEBOLD.
